National Brush Company, Aurora, Ill., a corpora-
tion of Illinois

Application August 23, 1938, Serial No. 226,324

20 Claims. (Cl. 300—4)

My invention relates in general to automatic machinery wherein a single machine accomplishes a number of related operations to manufacture a single complete product. More in particular, my invention relates to improvements in a power driven automatic machine for making brushes of various types.

Automatic machinery for making brushes of various types employing fibrous or relatively fine wire stock secured by means of staples in a back of wood or similar material, has been used for a relatively great number of years. Improvements have been made in this machinery through the years, but such machines prior to the present invention still remained rather complicated mechanisms, which were relatively wasteful so far as the consumption of brush material was concerned, and relatively inefficient from the standpoint of speed and cost of operation of the machine. In addition, the dimensions of various elements of these machines had to be maintained within narrow limits, and the co-action of elements had to be so precise and accurate due to the peculiar construction of the machines that almost constant machining and repair has been necessary to maintain such machinery in even fairly efficiently operating condition. Unless this precision is maintained the quality of the brushes manufactured thereby decreases perceptibly, and, of course, the rejects increase materially in number. This results in high maintenance costs and, of course, results in the machinery being out of use for a considerable part of the normal operating time. Furthermore, even with the high maintenance costs, there has still been a lack of uniformity in the product, and manufacturing costs have been increased as the number of rejects increases. In such prior brush-making machines, difficulties have also been encountered in using all types and qualities of brush stock, the machines requiring the more expensive grades of stock for automatic operation in some instances, thus increasing costs of production.

It is an object of the present invention to provide an automatic brush-making machine which is improved over the prior art machines in all of the elements and portions thereof which have been troublesome heretofore.

It is a further object of my invention to provide a simplified high-speed automatic machine for making brushes which operates at high efficiency and with very small maintenance costs.

It is also an object of my invention to provide a machine which will manufacture brushes which are superior in quality and uniformity to similar

brushes manufactured by the prior art machines.

Another object of my invention is to provide such a machine which will operate satisfactorily upon a greater number of different types and qualities of brush stock in the manufacture of the brushes, so that a wider range of brush materials both as to cost and texture, may be employed, to in turn provide for greater flexibility of the machine as to variations of the manufactured product and the selling price therefor.

One of the features of the machine of my invention is a reciprocating picker bar for receiving a measured quantity of brush stock from a stored supply while the bar is stationary and then quickly and cleanly separating such quantity from the supply and packing it into a tuft while at the same time carrying such tuft into position to be driven into a brush block. In the picker bar and cooperating packer bar of my invention, a uniform quantity of stock is removed from the supply magazine during each operation of the picker bar regardless of the clinging quality or softness of the brush material being worked upon, and the individual strands are normally in alinement. A picking operation is accomplished, furthermore, in a manner such that the material is separated cleanly from the remaining stock in the supply magazine without substantially any pieces dropping therefrom to be entirely wasted. In addition, the material is packed into a narrow slot so that a staple may be passed thereover quite easily. This permits simplification of the staple-forming mechanism, which simplification is another feature of the invention.

35 A further feature of my invention is the provision of a relatively simple pivoted wire-carrying and staple-forming jaw portion performing its function in a complete brush-making operation of the machine in timed relation to the picker bar so that a staple is ready to straddle the tuft in the bar and move therewith to the brush block as will be explained. In the corresponding mechanism employed in the prior art machines complicated reciprocating apparatus including a slide

45 was provided which had a relatively large number of moving parts carried in guide slots and the like so that in the position of such mechanism on the complete machine, dust and other foreign substance arising from the brush-making operation accumulated in the lubricated parts and readily clogged such parts making relatively frequent shut-downs necessary.

50 A still further feature of my invention is the provision, in a simpler and improved form, of 55 staple-carrying fingers mounted on a vertically

reciprocating block and adapted to form the staple on the staple-forming jaws, and then place the staple over the tuft carried in the picker bar to double up such tuft and carry it down through the frame of the machine to a brush block in position therebelow, where the staple with the tuft therein is positioned over a corresponding aperture therein, and driven into the block by a punch slideable intermediate said fingers. A precision cam structure between the punch and fingers was provided in the prior art machines which had to be machined, and then repaired, at frequent intervals to maintain this precision relationship, thus providing expensive maintenance costs and taking the machine out of operation much of the time. The careful machining of the prior art structures is eliminated and much higher efficiency at a great deal lower maintenance cost is obtained.

Another simplification is obtained in connection with the driving mechanism for these staple-carrying fingers. In prior art machines the fingers were mounted on a slide which was driven by a bell crank through a complicated link structure including two cross-heads and two adjustable connecting bars. Although this complicated adjustable structure may be desirable in some instances, in a commercial embodiment of my invention I have substituted therefor a simple one piece link for the complicated link of the prior art.

A further feature of my invention is one which relates to increasing the output of the machine by virtue of having less idle time during normal operation. Heretofore, the brush blocks have been secured in place manually and released manually, and during this operation the machine would have to stand idle. According to the present invention the blocks are released automatically when the work thereon is completed and the blocks then inserted are clamped automatically as the machine is started in the usual way for its next run. Furthermore, this mechanism is coupled with simplified improved control structure for the machine as a whole and particularly the table upon which the brush blocks are releasably retained.

One of the outstanding advantages of the machine of my invention is the high speed automatic operation obtained substantially without waste when making brushes with any type of quality of brush stock, and producing a brush having tufts with uniform bulk throughout, thereby reducing the rejects to a minimum, and increasing the general quality of the finished products. This advantage is obtained in continuous operation of the machine over long periods of time with substantially no maintenance or repair except the normal lubricating, so that the machine is operating at maximum efficiency for practically the entire available working time.

Other objects, features and advantages of my invention will be apparent from the following description taken with the drawings, in which:

It is believed that the invention as a whole can be best understood after understanding the general operation of the machine. This general operation can perhaps best be explained by briefly describing the course of the bristles of the brush from the magazine 11 to the brush block 12, into which tufts of the bristles are secured by staples to form the brush.

General operation

The magazine 11 contains a supply of stock B which may be any suitable material such as bristles, hairs or fine wire which are neatly arranged side by side in a horizontal position. It is necessary to separate a tuft of the stock from the supply of stock in the magazine 11, and this is accomplished by means of a reciprocating picker bar 13 which slides on table 15 and which has a slot or notch 14 therein, into which the proper quantity of the stock B is scooped by a claw 16. The construction and operation of the picker bar 13 and its associated parts is an important part of the invention, which is discussed in detail below. It is sufficient for the present to mention that the notch 14 is relatively narrow and that the stock is positively forced therein by co-action between the claw 16 and a wiper or packer block 17 which also insures a clean separation of the stock for the tuft from the supply stock.

The picker bar 13 carries the stock for the

tuft to a position under a pair of staple-carrying fingers 18 and also under a wire-carrying anvil 19 on which a cut length of wire S is held by a jaw 21. The wire-carrying fingers 18 move downwardly to bend the wire S about the anvil 19 to form a staple, after which the anvil is withdrawn. The mounting of the anvil comprises another feature of the invention and is described in detail below. As the anvil is withdrawn, the staple is carried down and applied in a straddling position over the center of the tuft stock in the notch 14. As the fingers 18 continue their downward movement through or adjacent to the picker bar 13, they double up the tuft stock to form a tuft and carry it with the staple into juxtaposition with the brush block 12 which will previously have been drilled with holes to receive the tufts. During the downward movement the fingers 18 may be moved slightly toward one another by engaging rollers 22 so as to compress the staple slightly, to compact the tuft better, and to insure its fitting into the hole in the brush block 12. This also insures that the staple will be held firmly by the fingers 18.

When the fingers 18 have carried the staple with the tuft therein into juxtaposition with the brush block 12, a staple driver 23 positioned between the fingers 18 drives the staple into the block 12 to secure the tuft therein. As the parts return to the position shown in Fig. 1 a set of cams including the cam 24 (Fig. 12) move the table 26, on which the brush block 12 is secured, to a position to insert the next tuft in the block 12 and also move the guard member 27 in such a way as to keep the tufts already in the brush out of the way of the tuft being applied, which is carried through the guard 27 by the fingers 18. When the entire brush is completed, the brush block 12 is automatically released by operation of an air cylinder 28 and a clamp 29 controlled thereby. This automatic release of the brush 12 and the subsequent automatic clamping of the new brush block comprises another feature of the invention and is described in detail below.

Detailed description

The picker bar 13, whose operation was generally described above, is seen best in Figs. 3 to 8. In Fig. 3 it is seen in its left-hand position with the notch 14 empty. The brush stock B in magazine 11 rests on a retaining surface 31 formed by the top of a bar 32 which is one portion of the picker bar 13. In addition to the portion 32, the picker bar 13 includes a portion 33 which is adjustably spaced from the portion 32 by a connecting bar 34 which is rigidly secured to the portion 32. The portion 33 is firmly clamped to the connecting bar 34 by screws 36 which pass through a slot 37 in the portion 33 and screw into a clamp member 38 which has an extension 39 thereon, which for convenience may be called the side rest of the picker bar 13. By loosening screws 36 the size of the notch 14 can be adjusted.

The claw 16 is preferably formed as the end of a plate 41 which is secured in a longitudinal recess 42 of the portion 33. The top of the plate 41 and hence the point or leading edge of the claw 16 are spaced slightly above the retaining surface 31 and therefore, as the picker bar 13 is moved to the right as seen in Fig. 3 by any suitable mechanism represented by link 43, the claw 16 will tend to scoop into the notch 14 all of the stock resting on the surface 31 which is below the top of the claw 16. In other words, the claw 16 slices through the supply of brush

stock B and separates that quantity which is to be used in the instant tuft from the rest of the supply. This quantity is accurately measured by the height of the point of the claw 16 above the retaining surface 31 and by the width of the magazine 11 from a fixed wall 44 to an adjustable wall 45. The brush stock B is kept under a relatively constant pressure by a weighted plate W seen in Fig. 1.

Because of the large cross-sectional size of the wide space between the walls 44 and 45 of the magazine 11, the brush stock B moves readily against the surface 31 so that it always fills the space thereabove in the magazine 11 with uniform compactness. It is, however, a very different matter to get this stock into a notch such as the notch 14 and particularly into one as narrow as is the notch 14. With many types of brush stock and with the notch as narrow as is often desired for the notch 14 the effect of the weighted plate to merely press the stock into the notch 14 by gravity would be entirely inadequate, even if the notch 14 opened directly upwardly as in the prior art machines. According to the present invention, however, the stock is forced into the notch 14 very effectively by co-action between the claw 16 and the buffer or packer block 17. The packer block 17 may conveniently be made up of two portions, namely a main portion 47 and a side plate 48. These two members are rigidly secured together and are rigidly mounted upon a fixed bracket 51 on the machine frame. The main portion 47 of the packer block 17 slidably engages the retaining surface 31. As the picker bar 13 slides to the right in Fig. 3, the plate 41 passes through a channel 52 in the packer block 17. It will be observed, in other words, that the packer block 17 overlaps the plate 41 on both sides with the result that there is no chance for the brush stock to pass between these two members, and therefore that which has been scooped into the notch 14 is separated with certainty from the remaining supply in the magazine 11. Furthermore, the side plate 48 of the packer block 17 extends below the retaining surface 31 so as to minimize any tendency of the stock to cling to the surface 31 and pass under the main portion 47 of the packer block 17. Furthermore, both the side plate 48 and the main portion 47 are tapered at their leading ends, the ends facing the claw 16, so that they exert a packing effect on the brush stock within the notch 14, pressing this stock firmly down into the notch. The tapered or beveled end portions also cooperate with the claw 16 in separating the brush stock within the notch from that in the magazine more effectively than if vertical ends were employed, for instance. The cam shaped portion of the packer block 17 should extend high enough at its end to be positioned over the stock which is in the highest position in which it can be left by the packing-down action of the claw 16. The portion 33 may be positioned entirely below the level of retaining surface 31 so as to insure adequate clearance.

The shaping of the parts is very important in obtaining uniformly satisfactory separation and packing of the stock for the individual tufts. Various features of this shaping are seen best in Figs. 3 and 5. The underportion of the claw 16 is rounded so as to direct the stock gently down into the notch 14. The upper corner 52 of the portion 32 adjacent the claw 16 is also beveled or rounded to facilitate the passage of

the stock therearound. The leading corner 55 of the portion 33 is also beveled or rounded so as to facilitate the compacting of the stock down into the notch 14 by action of the packer block 17.

The notch 14 is in reality a slot or passage between the portions 32 and 33 of the picker bar 13. The tuft stock which is packed into this slot 14 is restrained from falling therethrough by resting on the connecting bar 34 at one side and on the side rest 39 at the other side. It will be observed that the side rest 39 is spaced from the main portion of the picker bar at the position of the slot 14. The space between the side rest 39 and the picker bar 13 is provided to permit the passage of the fingers 18 therethrough. Thus, after the picker bar has moved to the right to separate a tuft of stock from the supply in magazine 11, it continues to the right to position this tuft under the fingers 18.

Figs. 17 to 19 inclusive, illustrate a modification, but in some respects a preferred embodiment as to the picker bar and packer block portions of the complete machine of my invention. Although a relatively rigid sliding connection between the packer block 17 and picker bar 13 has been found satisfactory on the smaller brush machines embodying my invention, a resilient sliding connection has been more satisfactory in the larger machines. Such a connection is accomplished by supporting the picker bar 13 on a floating channeled plate 170 resiliently supported in a channel 171 in the machine table 15, as shown particularly in Figs. 17 and 18. The plate is supported therein by a plurality of springs 172 carried in additional cavities 173 in the table 15, and surrounding adjusting screws 174 which extend from underneath the table upwardly for threaded connection with the plate 170. These screws may be employed to originally level the plate 170 as desired, and at the same time act to adjust the spring tension in the springs 173 by virtue of the leveled or adjusted position of the plate 170 and the axial length of the springs. The picker bar 13, which is identical with that previously described, is moved with a reciprocating action in the channel 176 in the plate 170. This channel corresponds to the channel cut directly in the table 15, as shown in Figs. 5 and 7.

With this mounting for the picker bar 13, the latter is urged upwardly against a packer block 17' rigidly supported by the fixed bracket 51 on the machine frame. The packer block 17' comprises a one-piece member as contrasted to the two piece packer block 17, but includes a channel 52' longitudinally thereof to receive the claw 16 and portion 41 of the picker bar 13 in the same manner as previously described. The leading ends of the packer block 17' are beveled or tapered in the same manner as described with reference to the packer block 17, but with this embodiment of the invention it is unnecessary to provide the plate 48 with a cam-shaped lower edge, and the back portion of the packer block 17' corresponding to that portion represented by the plate 48, and packer block 17 extends toward the fingers 18 with a straight line edge parallel to the straight line edge of the front portion of the packer block 17' as can be seen in Fig. 17.

The tuft, as T, which would normally be carried in the slot 14, but which is not illustrated in Fig. 17 due to the position of the picker bar in that figure, is compressed therein by means of a generally U-shaped member 177 illustrated

in detail in Fig. 19. This member includes a mounting portion 178 for securing to the bracket 179 from which the magazine plate 45 is adjustably supported. The member 177 is mounted for vertical adjustment only, in order to vary the distance of the same from the packer block 17' as will be described. The member 177 comprises a pair of legs 181 and 182 extending in a generally U-shape from the mounting portion 178 and at right angles thereto for straddling the reciprocating picker bar 13. Each leg has a rounded or cam-shaped portion 183, at such a position therein as to lie substantially below the leading end portion of the packer block 17' as can be seen in Fig. 17. As the picker bar 13 moves to the right, as illustrated in Fig. 17, with a full tuft in the slot 14 received from the magazine 11, such tuft is pressed upwardly by the cam portions 183 to be compressed intermediate such portions and the lower surface of the packer block 17'. This action also assists in the operation of separating the tuft from the stock in the magazine. The right-hand end of the leg 182 of the member 177 is off-set to permit the fingers 18 to extend downwardly therethrough, and an up-turned end 184 is provided on each of the legs 181 and 182, to act as stops in some instances for the tuft and consequently for the picker bar 13.

As shown in Fig. 17, five sets of screws 174 and springs 172 thereon are provided for supporting the plate 170 substantially over the length thereof. This number may be varied as desired so long as a proper balance is maintained by the plate 170 and packer block 17' so that the picker bar slides over a level but resilient base. It is also understood that this resilient mounting for the picker bar 13 may be satisfactorily employed with the packer block 17 without the use of the member 177.

Before describing in detail the operation of the fingers 18 it may be best to describe the manner in which the cut length of wire S is supplied thereto. Referring now to Fig. 13, it is seen that a continuous length of wire 56 is supplied to the machine from any suitable reel, not shown. This wire is intermittently fed by a pair of rollers 57, at least one of which is driven and knurled. The driven roller 57 is driven intermittently so as to feed the wire between operations of the cutter. The intermittent drive may be in the form of a ratchet wheel 58 and pawl 59 driven by an eccentric 61 on a shaft 62, which shaft will of course be driven in timed relation with the rest of the machine.

Through another eccentric on shaft 62 a bell crank lever 63 is driven to reciprocate a sleeve 64 pivoted thereto, which adjustably carries a link 65, and this in turn reciprocates a wire cutter 66 which reciprocates through a guide 67 to cut the wire when a suitable length thereof has been fed and grasped between the anvil jaw 19 and the wire-holding jaw 21 as seen in Fig. 16. The cutter 66 preferably cuts the wire at an angle of approximately 45° so that when the wire is bent to the form of a staple its ends will be pointed. The anvil jaw 19 is pivoted by a stud or screw 68 near the front end of the anvil to a forward extension of a carrier plate 69. The holding jaw 21 is pivoted at its rear end at 71 to the carrier plate 69 and is drawn toward the anvil jaw 19 by a spring 72. The counter-clockwise pivoting of the anvil jaw 19 may be limited by co-action between a slot 73 therein and a pin 74 secured to the plate

69. The jaws 19 and 21 are provided with interacting projections 76 and 77 so located that a downward pressure on the anvil jaw 19 and the consequent clockwise pivoting thereof will raise the holding jaw 21 to release the wire S. The clockwise pivoting of the jaw 19 is limited by the tail 78 of the jaw 19 which will strike the pivotal portion of the jaw 21.

After the jaws 19 and 21 grasp the wire S, this wire is cut by the cutter 66 and the jaws 19 and 21 carry the wire to the position shown in dotted lines in Fig. 16 under the fingers 18. The fingers 18 are driven downwardly and bend the wire S about the anvil 19. In so doing they pivot the anvil clockwise and raise the holding jaw 21. When the bending of the wire to staple form is complete, the jaws 19 and 21 carried by the plate 69 are withdrawn to the position shown in full lines in Fig. 16. The wire or staple S is restrained from being drawn away from the fingers 18 by virtue of notches 80 beginning at the ends of the fingers and extending upwardly on the insides of the fingers. While the jaws 19 and 21 are in their forward position shown in dotted lines, a new portion of the wire is fed between them through the space 79. As the jaws are withdrawn they will slide along this portion of the wire which will force them open until it is positioned and held between the ends of the jaws, in a notch in jaw 21.

The plate 69 carrying the jaws 19 and 21 is mounted in an extremely simple manner according to this invention, being carried by a long arm 81 which is pivoted at 82 to an upright frame portion 82 of the machine. The arm 81 is urged rearwardly by a coil spring 84 which is sprung between the arm 81 and a portion of the frame 83. The rearward movement of the arm 81 is adjustably limited by a screw 86. The arm 81 is driven forwardly by a cam 87 keyed to shaft 62 and having a projecting cam portion 88 which engages a cam follower roller 89 carried by the arm 81. The roller 89 is mounted in a slot 91 in the arm 81 so that the forward position of the arm 81 and consequently of the cut wire S may be adjusted.

When the wire S is positioned below the fingers 18 by the jaws 19 and 21, the fingers 18 are driven downwardly. The driving force comes from a pivoted lever 93 which is driven by a crank 94 carried by a shaft 95 which is connected to shaft 62 by gears or a chain and sprockets so that they are driven synchronously. The lever 93 is connected to a slide 97 which slides in a suitable guideway 98 in the frame 83. The slide 97 drives the staple driver 23 which is adjustably secured to the slide 97. It also drives the fingers 18 through a bell crank 99 which makes the fingers 18 move irregularly with respect to the slide 97. The bell crank 99 is pivoted at 101 to an arm 102 carried by the slide 97. On one end of the bell crank lever 99 is a roller 103 which rides in a groove 104. The other end of the bell crank lever 99 is connected by a simple link 106 to a second slide 107, to which the fingers 18 are pivoted at 108. When the roller 103 is riding in a vertical portion of the groove 104, there is no pivoting of the bell crank 99 and as a result the slide 107 with the fingers 18 move at the same rate of speed as does the slide 97. However, there are two jogs 109 and 110 in the groove 104. Upon downward movement of the slide 97 each of these jogs pivots the bell crank lever 99 in a clockwise direction

as seen in Fig. 1. This pivotal movement alone would raise the slide 107 and fingers 18, but since it is accompanied by a downward movement of the slide 107, and hence of the bell crank 99, it merely operates to hold the slide 107 and fingers 18 stationary.

The first of these jogs 109 is positioned to hold the fingers 18 stationary after they have bent the wire S about the anvil 19 to form the staple while the staple driver 23 is moved into position approximately at the staple, to back up the staple and prevent it from sliding up into the fingers. The fingers are at their maximum separation at this point and there is less friction on the staple than subsequently in the complete operation. The second jog 110 holds the fingers 18 stationary in juxtaposition to the brush block 12, while the slide 97 and staple driver 23 continue downwardly to drive the staple into the block 12.

It will be observed from Fig. 10 that as the fingers 18 are moved downwardly they initially bend the staple about the anvil 19 so that the staple legs form a V-shape. This results from the fact that the width of the anvil is less than the distance between the fingers. The staple legs remain spread until after they have straddled the tuft T. This is less necessary than it was in the prior art picker bars where no such narrow tuft could be formed as is possible with the picker bar of my invention, but it is still desirable in the interest of the speed to have the staple legs straddle the tuft T without any interference. The staple is compressed after it has engaged the tuft T and after such compression the staple legs are substantially parallel. The rollers 22 are provided to cooperate with the fingers 18 for the compressing operation. As seen in Figs. 1 and 9, these rollers 22 are supported on studs 110 carried by brackets 112 which are adjustably secured on the table 15 of bolts 115 so that they may be accurately positioned to compensate for wear or to adapt the machine to a variety of brushes. As is evident from Figs. 3 and 9 the rollers move in a cavity in the table 15. The rollers 22 engage cam surfaces 113 formed by the outside edges of the fingers 18.

As the fingers 18 approach the brush block 12, the cam surfaces 113 strike the rollers 22 which press the fingers 18 toward one another slightly thereby compressing the staple S and compacting the tuft T. The amount that the staple S is compressed will depend upon the size of the hole in the block 12 into which the staple and tuft are to be driven. Ordinarily the compressing will be very slight, perhaps in the nature of one-sixteenth of an inch. This construction eliminates the original expensive machining required in the prior art cam mechanism for accomplishing the compression, and eliminates the substantially constant maintenance necessary on the prior machines which also involved a serious loss of the use of the machines while repairs were being made.

In order for the staple to straddle the tuft easily and cleanly, and of greater importance, in order to have a firm uniform tuft in a brush, it is necessary for the tuft to be quite well confined. This is accomplished by virtue of having the slot 14 relatively narrow and this in turn is made possible by virtue of the positive packing action of the claw 16 in combination with the packer block 17, or the packer block 17' and the compressing member 177 as has been previously noted.

As described above, the fingers 18 are pivoted on studs, or the like, 108 secured in the slide 107 (Fig. 9). It should be noted that the fingers 18 are normally urged apart by springs 116 and are limited in this outward movement by co-action between pins 117 and slots in the fingers 18. The pins 117 also carry a guide plate 118 which braces the fingers 18 and prevent any movement thereof except a pivotal movement about the pivots 108. One important advantage of the control of fingers 18 by rollers 22 is that the forces exerted on the fingers 18 are applied in a direction directly through the width of each finger, or stating it in another manner, no forces are exerted on the fingers 18 which tend to twist them or move them in any way other than about the pivots 108. This prevents any uneven wear on the pivots 108 or other parts, and such slight wear as there may be on the cam surfaces 113 is readily taken up by adjustment of the brackets 112. It should also be noted that, as the fingers 18 carry the staple down over the tuft T and on down between the picker bar 13 and its side rest 39, the tuft is enabled to slide smoothly from its position in the picker bar 13 by virtue of the rounded surfaces 119 and 120 of the connecting member 34 and the side rest 39.

As previously mentioned, the brush block 12 is held in place by clamp 29 which is actuated by a fluid cylinder 28. The fluid cylinder 28 (Fig. 1) is controlled by a valve 122 (Fig. 12) mounted on the frame of the machine, and operates when the valve plunger 123 is in the position shown (supplying air to cylinder 28 through hose 124) to thrust the clamp 29 against the brush block 12. When the valve plunger 123 moves to the left, it closes the connection between the air supply hose 126 and the hose 124 and opens the hose 124 to the exhaust vent 121. This permits the air to escape from the cylinder 28 so that the clamp 29 is drawn away from the block 12 by springs 128, seen best in Fig. 2. The operation of the valve plunger 123 and hence the operation of the clamp 29 are automatic.

As seen in Fig. 12, the valve plunger 123 is held in the right-hand position, as shown, by a cam 131 which in turn is held against rotation by a pawl 132. The cam 24 is shown in the last position during the operation on one brush block (or rather on a pair of brush blocks since holes are drilled in one block while the tufts are secured in another block). As the block is finished, cam 24 will rotate to thrust its follower roller 133 on pivoted lever 134 to the left so that pawl 136 catches in a notch 137 in an adjustable lock bar 138, stopping the machine. At the same time lever 139 rotating with cam 24 strikes the tail 141 of pawl 132 to release cam 131. The fluid or spring pressure on valve plunger 123, or a separate spring if desired, causes the cam 131 to rotate counter-clockwise as seen in Fig. 12 until an associated arm 142 strikes a stop 143. The movement of the cam 131 permits the plunger 123 to shift to its left-hand position thereby releasing the clamp 29 or rather releasing a clamp 29 on each of the brush block tables. The finished brush is then removed, the brush block which has just been drilled is manually placed on the tufting table, and a new brush block is placed on the drilling table. A trigger 144 on handle 145 is then squeezed to release pawl 136 so that the machine can be started in operation again. Since the high point of the cam 24 has now passed the roller 133, the lever 134 will be drawn inwardly by a spring 147 until the roller

133 engages the low point of the cam. During this movement a dog 148 on lever 134 will strike arm 142 and rotate the cam 131 to the position shown in Fig. 12 thereby shifting the valve plunger 123 to the right-hand position. This opens the air supply to the air cylinder 28 and operates the clamps 29 against the brush blocks, thus beginning the automatic operation of the machine. It may be noted that the handle 145 is associated with the brush block holding tables 26 which may be pivoted at a variety of points 149 therebelow depending on the design of the brush.

The detailed discussion of the operation of the machine is included in the foregoing description and the general discussion of the operation appears under a separate heading before the detailed description and therefore need not be repeated here. From the foregoing it is evident that a brush-making machine has been provided which is both simpler and more efficient than such machines used heretofore. It separates the tufts from the supply of brush stock with little or no loss and with great uniformity. It confines the tufts more narrowly so that a more compact, rugged tuft will be secured in a brush to in turn provide a brush of better quality, and so that a staple with approximately parallel sides and a narrower opening may be applied thereover. It is more adaptable to different brushes because of the dependability of the tuft-separating device with all kinds of brush stock and because of the readiness with which the width of the staple can be adjusted. Lost machine time is greatly minimized both during normal operation by virtue of automatic clamping means for the brushes and also as to shut-downs for repairs since the parts which have heretofore needed frequent repair or cleaning have been so greatly simplified that such repair and cleaning are now substantially eliminated.

Although I have described my invention in its preferred embodiment, it is understood that I do not limit the invention thereby, but limit the same only by the scope of the appended claims.

I claim:

1. In a brush-making machine, a magazine for brush stock having an open end toward which the brush stock is biased in a direction perpendicular to the individual pieces thereof, and means for separating a tuft from said brush stock, including a picker bar having a slot therein and reciprocating adjacent the open end of the magazine, and having a retaining surface extending horizontally away from the slot on one side thereof and at times positioned to receive the stock thereon at the open end of the magazine, a separating claw extending from the other side of the slot overhanging the slot and dimensioned to extend to a height greater than the height of the horizontal retaining surface, and stationary packing means positioned at one side of the open end of the magazine and always entirely out of said open end for preventing movement of the stock with the retaining surface as the picker bar reciprocates whereby said claw scoops the stock resting on said horizontal surface into said slot thereby forcibly separating it from the remainder of the stock in the magazine, said packing means including a packing portion which extends downwardly beyond said retaining surface, and a separating portion substantially in engagement with said horizontal surface extending laterally away from the vertical direction of the magazine with an upwardly beveled face acting to

minimize the tendency of the stock to catch between said packing means and the retaining surface.

2. In a brush-making machine, a magazine for brush stock having an open end toward which the brush stock is biased in a direction perpendicular to the individual pieces thereof, and means for separating a tuft from said brush stock, including a bi-part picker bar having a slot intermediate the two parts thereof and reciprocating adjacent the open end of the magazine, with one of said parts having a retaining surface extending away from the slot on one side thereof and at times positioned to receive the stock thereon at the open end of the magazine, a separating claw on the other part extending from the other side of the slot overhanging the slot and dimensioned to extend to a height greater than the height of the retaining surface, and packing means for preventing movement of the stock with the retaining surface as the picker bar reciprocates whereby said claw scoops the stock resting on said surface into said slot thereby forcibly separating it from the remainder of the stock in the magazine, said packing means including a stock separating portion substantially in engagement with said surface and a packing portion extending downwardly below said surface, with said packing means having a channel between said portions for receiving the claw with a sufficiently close fit so that with said packing portion the stock is positively forced down into said slot.

3. In a brush-making machine, means for separating a tuft of stock from a supply of stock, including a magazine for holding the supply of stock in parallel arrangement, reciprocating means including a claw adapted to be moved from one side of said magazine entirely across the same for slicing between the stock, to form a given tuft, and the remainder of the stock, and positively drawing the former from the latter, and means for cleaning said stock from said claw including a packer block having a channeled under portion with side-wall portions adapted to straddle the claw as it leaves the supply of stock, with one of said side-wall portions having an end toward said magazine with a face thereon being bevelled laterally away from said magazine and upwardly to form substantially a pointed portion for engagement with the stock.

4. In a brush-making machine, a magazine for brush stock having an open end toward which the brush stock is biased in a direction perpendicular to the individual pieces thereof, and means for separating a tuft from said brush stock, including a picker bar having a slot therein and reciprocating adjacent the open end of the magazine and substantially entirely across the same, and having a retaining surface extending horizontally away from the slot on one side thereof and at times positioned to receive the stock thereon at the open end of the magazine, a separating claw extending from the other side of the slot at a height greater than the height of the retaining surface and overhanging the slot, said picker bar having a portion abutting said claw on the same side of the slot therewith which portion is of a lower height than said claw, and stationary packing means for receiving said claw in a straddling position and acting to prevent movement of the stock with the retaining surface as the picker bar reciprocates whereby said claw scoops the stock resting on said surface into said slot thereby forcibly separating it from the remainder of the

stock in the magazine, the slot and claw being shaped to form a relatively smooth passage to permit the smooth flow of the stock thereinto, and the lower portion abutting said claw extending to said slot and having an end wall at the slot adjacent the claw rounded, and the leading end of the packing means being beveled away from the leading end to facilitate the packing-co-action between the stationary packing means and the reciprocating picker bar.

5. A brush-making machine, including an open-ended brush stock retaining magazine having brush stock therein, a reciprocating picker bar for removing a substantially measured tuft from said brush stock in the magazine with said picker bar movable across the open end of said magazine, packer means above said picker bar and resilient means on said machine below said picker bar yieldingly supporting said reciprocating picker bar, over substantially its entire reciprocating path and urging said picker bar upwardly against said packer means.

6. A brush-making machine including an open-ended brush stock retaining magazine having brush stock therein, a reciprocating picker bar for removing a substantially measured tuft from said brush stock in the magazine with said picker bar movable across the open end of said magazine, packer means cooperating with said picker bar to act on the tuft, means on said machine yieldingly supporting said reciprocating bar comprising a member below said picker bar having an elongated channel therein for receiving said picker bar, and resilient means supporting said member for urging the same upwardly to in turn urge said reciprocating picker bar upwardly against the packer means.

7. A brush-making machine including a rigid frame, a brush stock magazine supported on said frame having a supply of brush stock therein, a picker bar reciprocatingly movable across one end of said magazine having an extending claw thereon for cutting through a substantially measured quantity of brush stock resting on one edge of said picker bar when said picker bar is beneath said magazine in a loading position, a packer block supported on said frame in the path of movement of said picker bar and adapted to cooperate therewith for separating said substantially measured tuft from said brush stock in the magazine, and means for yieldingly supporting said picker bar including a resiliently mounted supporting member acting to press said picker bar upwardly against said packer block.

8. In a brush-making machine a brush stock magazine having a supply of brush stock therein, means for separating a substantially measured tuft from said brush stock in the magazine including a reciprocating picker bar movable across an open end of said magazine and having a brush-tuft receiving slot therein, a packer block supported on said machine above said picker bar in a position to close said slot during a portion of the movement of said picker bar, and means for compressing the tuft in said slot against said packer block including a pair of rigidly supported members with one of said members on each side of the picker bar and each of said members having a raised portion therein adapted to engage the tuft in said slot and raise the same against the packer block above said picker bar.

9. In a brush-making machine, staple-forming and carrying apparatus including a vertically reciprocating block, a pair of wire-engaging fin-

gers secured to said block by a pivot at one end of each finger with each finger being entirely pivotally movable at such pivot, means for presenting a wire to said fingers and for cooperating therewith to bend the wire to form a staple, means for positioning a tuft to be engaged by the staple and for confining it sufficiently for it to be readily straddled by the staple, means for moving the fingers to carry the staple and the tuft therein to a brush block, and means for compressing the staple to pinch the tuft laterally as it is moved toward the brush block including stationary means acting directly on each finger intermediate the two ends of each finger and co-acting with the fingers to press said fingers toward one another.

10. In a brush-making machine, staple-forming and carrying apparatus including a reciprocating block, a pair of wire-engaging fingers secured at one end to said block by pivots, means for presenting a wire to said fingers and for cooperating therewith to bend the wire to form a staple, means for positioning a tuft to be engaged by the staple and for confining it sufficiently for it to be readily straddled by the staple, means for moving the fingers to carry the staple and the tuft therein to a brush block, and means for compressing the staple to pinch the tuft laterally as it is moved toward the brush block including a rotatable roller on a fixed axis corresponding to each finger and each engaging a finger to press said fingers toward one another, said rollers acting directly on the fingers in a direction within a plane perpendicular to and approximately centered in the pivots of the fingers whereby forces tending to twist the fingers on the pivots are avoided.

11. In a brush-making machine, staple-forming and carrying apparatus including a reciprocating block, a pair of wire-engaging fingers pivoted to said block, means for presenting a wire to said fingers and for cooperating therewith to bend the wire to form a staple, means for positioning a tuft to be engaged by the staple and for confining it sufficiently for it to be readily straddled by the staple, means for moving the fingers to carry the staple and the tuft therein to a brush block, and means for compressing the staple to pinch the tuft laterally as it is moved toward the block including stationary means co-acting with the fingers to press said fingers toward one another, said fingers being cam shaped on their outer edges substantially at the lower portions thereof to engage said stationary means.

12. In a brush-making machine, staple-forming and carrying apparatus including a reciprocating block, a pair of wire-engaging fingers pivoted to said block, means for presenting a wire to said fingers and for cooperating therewith to bend the wire to form a staple, means for positioning a tuft to be engaged by the staple and for confining it sufficiently for it to be readily straddled by the staple, means for moving the fingers to carry the staple and the tuft therein to a brush block, and means for compressing the staple to pinch the tuft laterally as it is moved toward the block including stationary means co-acting with the fingers to press said fingers toward one another, said fingers being cam shaped on their outer edges to engage said stationary means, and said stationary means being adjustable to produce variations in the action of the fingers without adjusting the moving parts of the machine.

13. In a brush making machine having recip-

rocating fingers for forming a staple from a cut length of wire and means for producing cut lengths of wire, the combination of means for carrying said cut lengths of wire from the position of their formation to the reciprocating fingers including an arm, axis means supporting said arm at one end, means for pivoting said arm about said axis means, and cooperating means at the other end of said arm and carried entirely thereby movable in an arcuate path with such other end of said arm to directly carry the wire to the fingers, said cooperating means including an anvil member pivotally carried by the arm, and a clamp member cooperating with the anvil member to hold the cut length of wire therebetween as the arm is pivoted.

14. In a brush-making machine, reciprocating fingers for forming a staple from a cut length of wire, means for producing cut lengths of wire, and means for carrying said cut lengths of wire from the position of their formation to the reciprocating fingers including a movable anvil member and a clamp member for cooperating with the anvil member to hold the cut length of wire thereon as the anvil is moved to present the wire to the reciprocating fingers, said clamp member being pivoted at one end, and said anvil member being pivoted near its wire-holding end and engaging the clamp member at a point remote from the pivot of the anvil but between the wire-holding end and the pivot of the clamp member whereby a slight rotation of the anvil likewise pivots the clamp and removes said clamp from clamping position.

15. In a brush-making machine, reciprocating members for forming a staple from a cut length of wire, means for producing cut lengths of wire and means for carrying said cut lengths of wire from the position of cutting to the reciprocating members, said carrying means including a rigid arm pivotally supported at one end thereof and free-swinging at the other end thereof, an anvil member and a clamp member each pivotally mounted on said rigid arm at the other end thereof in adjacent position for cooperating with one another in holding the cut length of wire therebetween, and each pivotable independently of the other a spring secured to said arm for normally pulling the arm and the anvil and clamp members thereon out of the path of movement of said reciprocating members, and driving means acting on said arm to urge said arm intermediate the two ends thereof toward said reciprocating members against the force of said spring.

16. In a brush-making machine, reciprocating fingers for forming a staple from a cut length of wire, means for producing cut lengths of wire, and means for carrying said cut lengths of wire from the position of cutting to the reciprocating fingers including an anvil member, and a clamp member for cooperating with the anvil member to hold the cut length of wire thereon, and an arm pivotally supported at one end for supporting said clamp member and anvil member directly thereon, with said clamp member and anvil member moving over a path extending through an arc of a circle described by the end of said pivoted arm, said reciprocating fingers being shaped to engage said wire and form the same over said anvil during the reciprocating movement of said fingers.

17. In a brush-making machine having means for separating a tuft from a supply of brush stock and presenting said tuft in a position to be driven into a brush block, means for carrying

said tuft to said brush block and securing it therein including a pair of vertically reciprocating staple forming fingers, and wire carrying and staple forming means comprising a pivotally supported arm and a pair of jaws each pivotally supported directly on said arm and movable therewith to carry a piece of wire between said jaws for presenting the same to said fingers, and with said fingers acting to engage said wire and bend the same over one of said jaws, and thereafter carrying the bent wire downwardly to straddle said tuft to carry said tuft therewith to the brush block.

18. In a brush-making machine, a table for carrying a brush block, means for operating on said brush block at a given position, automatic control means for moving the table to present various portions of the brush block to said operating means and for stopping movement when the brush is completed, a clamp on the table for holding the brush block, means including a fluid system, a fluid cylinder and piston for operating the clamp, a fluid control valve automatically operated by the control means for releasing the clamp when the operations on the brush block are finished, and means automatically operated upon starting the machine for operating the valve to actuate the clamp.

19. In a brush making machine a table for carrying a brush block, means for operating on said brush block at a given position thereof, clamping means on said table for releasably retaining the brush block thereon, means including a fluid system, a fluid cylinder and piston for operating the clamp, a fluid control valve for regulating the movement of fluid in said cylinder, said control valve having a spring pressed plunger therein and a plurality of valve parts

closed or remaining open depending upon the particular position of the plunger, automatic control means acting to determine the position of the plunger and control the movement of the table carrying the brush block thereon including an enlarged rotatable cam moving the table to present various portions of the brush block to said operating means and for stopping the movement of said table when the brush is completed, a release member movable corresponding to said cam, means operatively connecting said release member with said plunger to cause the movement of said plunger to release the clamp at the stopping position of said table, and manually operated means for originally setting said table and actuating said control valve for clamping a brush block thereon.

20. In a brush-making machine having means for forming a staple from a cut length of wire, means for carrying a cut length of wire to said forming means including an arm pivotally supported at one end and free swinging at the other end, means intermediate the ends of said arm for swinging said arm toward the forming means, with said other end of said arm having a portion rigid with respect thereto, a wire-clamp member pivotally supported at one end on said portion, and an anvil member pivotally mounted on said portion with the pivot point thereof being intermediate the ends of said anvil member, said anvil member having a raised edge portion intermediate the pivot point thereof and the pivot point for said wire-clamp member, with said anvil member upon pivotal movement thereof acting at said raised edge to pivot said wire-clamp member to release a cut length of wire from between said anvil member and said clamp member.

JOHN G. BAUMGARTNER.
